FIGURE 1A

FIGURE 1 is a top plan view of the left side of a game board, showing our new design;

FIGURE 1A is a top plan view of the right side of the game board shown in FIGURE 1, and

FIGURE 2 is an edge view looking at the right-hand edge of FIGURE 1A.

The parts shown in FIGURES 1 and 1A are joined together in proper relationship to form the playing surface of the game board. In FIGURES 1 and 1A, the fragmentary indications of colors are continuous throughout the several areas, respectively, and the dominant features of the design are shown in full lines.

I claim:

The ornamental design for a game board, as shown and described.
